UNITED STATES PATENT OFFICE.

JOHN D. C. KNAPP, OF MINNEAPOLIS, MINNESOTA.

SEAL-LOCK.

SPECIFICATION forming part of Letters Patent No. 658,451, dated September 25, 1900.

Application filed March 27, 1900. Serial No. 10,318. (No model.)

To all whom it may concern:

Be it known that I, JOHN D. C. KNAPP, a citizen of the United States, residing at Minneapolis, in the county of Hennepin and State 5 of Minnesota, have invented certain new and useful Improvements in Seal-Locks; and I do hereby declare the following to be a full, clear, and exact description of the invention, such as will enable others skilled in the art to which

10 it appertains to make and use the same.

My invention has for its object to simplify and otherwise improve the construction of so-called "seal-locks" for freight-car doors; and to this end it consists of the novel 15 devices and combinations of devices hereinafter described, and defined in the claims.

The invention in its preferred form is illustrated in the accompanying drawings, wherein like characters indicate like parts throughout the several views.

Figure 1 is a view in side elevation showing my improved seal-lock applied in working position. Fig. 2 is a view corresponding to Fig. 1, but illustrating the manner in which 25 the sealing-block is broken by the opening movement of the hasp-hook or lock. Fig. 3 is an inner side elevation of the hasp removed from the door. Fig. 4 shows the parts illustrated in Fig. 1, partly in plan and partly in 30 horizontal section. Fig. 5 is a vertical section on the line $x^5 x^6$ of Fig. 4. Fig. 6 is a view corresponding to Fig. 5, but showing the sealing-block as removed and the detent as forced into its seat; and Fig. 7 is a plan view 35 showing the back of the sealing-block.

The numeral 1 indicates a portion of a car, and the numeral 2 indicates a portion of a car-door, both of ordinary construction.

The hasp-plate a is either of malleable or 40 wrought iron construction, and preferably the former. At one end it is secured to the car-door 2 by a suitable staple 3, and at its free end it is formed with a pair of longitudinally-extended and vertically-spaced staple-passages a' , through one or the other of which a projecting lock-staple 4, which is suitably secured on the car-body 1, is adapted to be passed, as shown in Figs. 1, 2, and 4. A lock-piece b is pivoted to the intermediate portion 45 of the hasp-plate a , as shown at b' , and at its free end the said lock-piece is provided with reversely-projected hook-pieces b^2 , that are

preferably turned on the arc of a circle struck from the center of the pivot b' and intersecting the central portions of the passages a' . 55 At their extreme ends the staple-hooks b^2 are adapted to be passed through the staple 4 after the said staple has been passed through one of the passages a' . The lock or hasp-hook should of course be arranged to engage 60 the staple 4 by downward movement, so that it will be held by gravity, even though the device is not sealed, and the double arrangement of the passages a' and hooks b^2 makes this possible regardless of which side up the 65 hasp-plate is turned. It will be understood that this is important, for the reason that if the hasp-plate were to be applied to a door mounted to open by sliding movement in a reverse direction from that indicated in the 70 drawings the said hasp-plate would necessarily be turned upside down. Obviously this hasp-plate and hook work the same either side up.

When the lock is sealed, a fragile or brittle 75 sealing block or piece is directly engaged with the base portion b^3 of the lock-hook b and engages the same in such manner that the said lock-hook cannot be moved without breaking the said sealing-block. The sealing-block or piece is preferably constructed from 80 a composition of clay and other materials baked hard and brittle; but it will of course be understood that glass or any other suitable material may be employed. The sealing-block 85 as preferably constructed is in the form of a thin and approximately-square plate f , having a marginal flange or reduced portion f' and a central recess or detent-seat f^2 . The flanged edges f' of the sealing-block f fit correspondingly-formed seats formed in a pair of parallel keeper-flanges a^2 on the hasp a . When the sealing-block f is positioned as shown in Figs. 1 and 4, its forward flange f' fits a correspondingly-formed ledge or seat b^3 at the base of 95 the lock-hook b , and the sealing-block being locked and held in the position indicated prevents movement of the said locking-hook b in either direction, and hence holds the same in its locked or locking position. 100

The sealing-block f is locked in its operative position above indicated by a spring-pressed detent g , which works through a seat a^3 in the back of the hasp-plate a and engages

into the detent-seat f^2 of the said sealing-block. On the back of the hasp-plate a , just outward of the passage a^3 , is an outwardly bulged or projected pocket a^4 , which is originally open at two ends and is provided at these open ends with projecting flanges a^5 . In case the hasp-plate is malleable iron the parts a^5 will be cast projecting as indicated by dotted lines in Fig. 4. After the detent g has been placed in working position, together with its spring g' and preferably, also, a spacing-block g^2 , the flanged ends a^5 are bent down, as shown by full lines in Fig. 5, and are there brazed or soldered to tightly close the pocket. The detent g , as preferably constructed is stamped from sheet metal or steel and has a marginal flange g^8 , which prevents the spring g' from forcing it through the seat a^3 in the hasp-plate a . The spacing-block g^2 , while not absolutely necessary, is very desirable, for the reason that it limits the inward movement of said detent g , as shown in Fig. 6, and thus prevents the said detent from being forced out of its seat a^3 .

As is obvious, to apply the sealing-block f in working position to hold the hasp-hook locked it is only necessary after inserting the said block into the keeper-guides a^2 to press inward on the spring-pressed detent g , so as to pass the sealing-block over the same and into a position in which its detent-seat f^2 registers with the said detent g , whereupon the said detent will spring into the said detent-seat. When the parts are thus interlocked, the sealing piece or block cuts off access to the detent, so that the said detent cannot be released, and hence the lock-hook b cannot be moved as long as the said sealing-block is unbroken.

The sealing-block may be quite easily broken by forcing the locking-hook into an open position, as indicated in Fig. 2. Under this movement of the locking-hook the brittle sealing-block is acted upon by the inturned base portion of the hook and is put under strain edgewise, so that the sealing-block is crushed into small particles.

By applying the strain to the sealing-block edgewise thereof or in the plane in which it is extended a sealing-piece of given strength will resist to the maximum a force tending to crush or break it and when it gives away will go to pieces all at once. On the other hand, if the force were to be applied to the sealing-block in the direction of its smallest dimensions it would be much more easily

broken and when broken would be likely to divide into but very few pieces. The pieces if but few and very large may sometimes be put together again and replaced in the seal. Hence the advantage incident to my arrangement of the seal-breaking device is evident.

It will of course be understood that the device above described is capable of considerable modification within the scope of my invention.

What I claim, and desire to secure by Letters Patent of the United States, is as follows:

1. The combination with a hasp or supporting plate, of the pivoted lock-hook having a transversely-extended base, a fragile sealing-piece directly engaging said base end of the lock-hook to hold said hook in an operative position, a seat or keeper holding said sealing-piece against lateral displacement, and a detent normally holding said sealing-block within its seat or keeper and against the base of said hook, which sealing-block extends in the plane of movement of said lock-hook and is adapted to be crushed by compression caused by the movement of said hook from its operative or locking position, substantially as described.

2. The combination with a hasp of a pivoted lock-hook b having the base end b^3 , of the keeper-guides a^2 , the spring-pressed detent g working through said hasp, and the fragile sealing-block f having the detent-seat f^2 , which detent g engages said seat f^2 to hold said sealing-block, and which sealing-block g engages the base b^3 of said hook b to lock the same and is adapted to be crushed by the unlocking movement of said hook b , substantially as described.

3. The combination with the hasp-plate a having the pocket a^4 keeper-guides a^2 , and passage a^3 , of the spring-pressed detent g , working through said passage a^3 , the lock-hook b having the base end b^3 and one or more hooks b^1 , and the fragile sealing-block f held by the keeper-guides a^2 and provided with the detent-seat f^2 engaged by said detent g , said sealing-block engaging the base b^3 of said lock-hook and adapted to be broken by the opening movement thereof, substantially as described.

In testimony whereof I affix my signature in presence of two witnesses.

JOHN D. C. KNAPP.
